Justus R. Kinney,
by Walter E. Lombard,
Atty.

UNITED STATES PATENT OFFICE.

JUSTUS R. KINNEY, OF JAMAICA PLAIN, MASSACHUSETTS.

LIFTING JACK.

Application filed February 28, 1924. Serial No. 695,861.

To all whom it may concern:

Be it known that I, JUSTUS R. KINNEY, a citizen of the United States of America, and a resident of Jamaica Plain, in the 5 county of Suffolk, in the State of Massachusetts, have invented certain new and useful Improvements in Lifting Jacks, of which the following is a specification.

This invention relates to lifting jacks 10 and particularly to devices of this character designed for use with motor vehicles, the wheels of which are provided with balloon tires.

The object of the invention is the production of a lifting jack of simple construction, the supporting member of which is adapted to be moved to a very low position so that it may be inserted readily beneath the axle of a vehicle when the tire is deflated.

The invention consists primarily of a revoluble screw having a carriage movable endwise thereof by means of a nut mounted therein with its thread coacting with the 25 thread of said screw.

The invention consists further of certain novel features of construction and arrangement of parts which will be understood readily by reference to the description of 30 the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents an elevation of a lifting jack embodying the principles of the present invention, the lower portion of the jack being shown in section.

Figure 2 represents an end view of the same, the carriage thereof being cut in section on line 2, 2 on Fig. 1, and

Figure 3 represents a horizontal section of same on line 3, 3 on Fig. 1.

Similar characters indicate like parts

throughout the several figures of the drawings.

In the drawings 10 is the base of the lifting jack, this base consisting of a bent plate having an inclined portion 11, a horizontal top portion 12 and its ends 13 brought together and connected by a rivet 14 as shown in Fig. 1.

The horizontal top portion 12 has an opening therein in which is positioned the lower end of a revoluble screw 15 having a bearing in the block 16 secured to the base 10 by rivets 17.

Between the block 16 and top portion 12 the screw 15 has mounted thereon and pinned thereto a bevel gear 18 the teeth of which mesh with a driving pinion 19 pinned to a short shaft 20 rotatable in bearings in the block 16 and the inclined portion 11.

The outer end of the shaft 20 is squared as shown in Figs. 1 and 2 at 21.

The squared portion 21 is adapted to receive the squared socket 22 pinned to the end of an actuating rod 23 which may be of any well known construction.

The screw 15 may be of any length desired.

The screw 15 is surrounded by a bent plate 24 the side walls of which are parallel and spaced apart, one side wall having two cylindrical openings 25, 26 therein in alignment with similar openings in the other side wall.

In the openings 25, 25 are disposed the trunnion ends of a cylindrical guide member 27 having a transverse hole 28 therein through which the screw 15 extends.

This member 27 may oscillate in its bearings 25 and forms a guide for said screw 15.

In the openings 26 are disposed the trunnion ends of another cylindrical member 29 having a threaded opening 30 extending transversely thereof the threads of which coact with the threads of said screw 15 which extends through said opening 30.

The ends of the plate 24 extend laterally from said screw 15 and are connected by rivets 31, this extension forming a support 32 on which the axle A is adapted to rest.

The upper edges of the extension 32 are inclined downwardly toward the screw 15 and when the axle A rests upon this support 32 and against the vertical edges 33 as shown in Fig. 1 there is very little danger

of the axle being displaced accidentally from the support 32.

When the load is positioned upon the support 32 the entire carriage 24 is liable to tilt or cant thereby making it difficult to operate the screw 15 unless some provision is made to prevent such tilting.

To accomplish this object the carriage 24 is provided with two transversely disposed pins 34 on each of which is disposed a grooved roller 35 adapted to travel over the periphery of said screw 15 when the carriage 24 is raised or lowered.

Owing to the use of these rollers 35 the carriage 24 may move freely lengthwise of the screw 15 whenever the latter is rotated.

Whenever it is desired to insert the support 32 beneath an axle A the carriage 24 is moved manually about the axis of the screw until about the right height is reached and then the support is placed beneath the axle and brought into contact therewith.

Further rotation of the carriage is prevented by the load upon the support 32 and if rotary movement is imparted to the screw 15 by the driving mechanism 18, 19 the carriage will be raised on account of the coaction of the threads of screw 15 and nut 30.

This makes a very simple but effective device for raising and lowering motor vehicles being particularly adapted for such vehicles equipped with balloon tires owing to the fact that the support 32 may be lowered well toward the base 10.

It is believed that the operation and many advantages of the invention will be apparent without further description.

Having thus described my invention, I claim:

1. The combination of a base; a screw unsupported at its upper end and the lower end of which is revolvably mounted in supporting bearings in said base; means between said bearings for rotating said screw and preventing its displacement; a carriage movable endwise of said screw having a support at one side of said screw; and a nut carried by said carriage coacting with said screw.

2. The combination of a base; a screw the lower end of which is revolvably mounted in bearings in said base; means for rotating said screw; a carriage movable endwise of said screw having a support at one side of said screw; a nut carried by said carriage coacting with said screw; rollers carried by said carriage preventing the tilting thereof by the weight upon said support; and a transversely extending member mounted in said carriage and having a cylindrical hole therethrough to receive said screw and form a guide therefor.

3. The combination of a base; a screw the lower end of which is revolvably mounted in bearings in said base; means for rotating said

screw; a carriage movable endwise of said screw having a support at one side of said screw; a nut carried by said carriage coacting with said screw; rollers carried by said carriage preventing the tilting thereof by the weight upon said support; and a transversely extending member mounted to oscillate in said carriage and having a cylindrical hole therethrough to receive said screw and form a guide therefor. 75

4. The combination of a base; a screw the lower end of which is revolvably mounted in bearings in said base; means for rotating said screw; a cylindrical member adapted to oscillate in bearings of said carriage and having a threaded hole extending transversely thereof, the thread of which coacts with the thread of said screw. 80

5. The combination of a base; a screw the lower end of which is revolvably mounted in bearings in said base; means for rotating said screw; a cylindrical member adapted to oscillate in bearings of said carriage and having a threaded hole extending transversely thereof, the thread of which coacts with the thread of said screw, and a guide member for said screw adapted to oscillate in bearings formed in said carriage. 85

6. The combination of a base consisting of a bent plate the ends of which are riveted together; a block secured within said base; a revolvble screw the lower end of which has a bearing in said block; a gear fixedly secured to said screw; a pinion meshing therewith; a shaft therefor revolvble in bearings in said block and plate; means for rotating said shaft; a carriage movable endwise of said screw; and a nut carried thereby coacting with said screw. 95

7. The combination of a base; a screw revolvably mounted in bearings in said base; means for rotating said screw; a nut on said screw having oppositely disposed cylindrical trunnions; a guide member on said screw having oppositely disposed cylindrical trunnions; and a carriage consisting of a bent plate surrounding said screw with its ends extending to one side of said screw and secured together to form a support, said plate having bearings for said trunnions. 105

8. The combination of a base; a screw revolvably mounted in bearings in said base; means for rotating said screw; a nut on said screw having oppositely disposed cylindrical trunnions; a guide member on said screw having oppositely disposed cylindrical trunnions; a carriage consisting of a bent plate surrounding said screw with its ends extending to one side of said screw and secured together to form a support, said plate having bearings for said trunnions; and members at the upper and lower ends of said carriage contacting with said screw to prevent the tilting of said carriage. 110

9. The combination of a base; a screw 120

revolubly mounted in bearings in said base; means for rotating said screw; a nut on said screw having oppositely disposed cylindrical trunnions; a guide member on said screw having oppositely disposed cylindrical trunnions; a carriage consisting of a bent plate surrounding said screw with its ends extending to one side of said screw and secured together to form a support, said plate having 10 bearings for said trunnions; and rollers at

the upper and lower ends of said carriage contacting with said screw to prevent the tilting of said carriage.

Signed by me at 746 Old South Building, Boston, Massachusetts, this 27th day of February, 1924.

JUSTUS R. KINNEY.
